UNITED STATES PATENT OFFICE.

GEORGE H. ZOUCK, OF ORANGE, NEW JERSEY, ASSIGNOR TO FRANKLIN RAILWAY SUPPLY COMPANY, A CORPORATION OF DELAWARE.

LOCOMOTIVE BOOSTER APPARATUS.

Application filed August 27, 1925. Serial No. 52,736.

This invention relates to what are now well known as booster motors for aiding locomotives in starting or at slow speeds on heavy pulls. Such motors are arranged to 5 drive an axle either on the locomotive or on the tender with which axle they are suitably connected when it is desired to make use of their power although under general running conditions, when the booster is not in use, it 10 is disconnected from the axle so that the booster parts can come to rest. The connecting and disconnecting operations are referred to in the art by the technical expressions entraining and disentraining or en- 15 trainment and disentrainment.

A controlling system for the booster motor must therefore be provided by means of which it is possible to entrain the motor when desired and disentrain it when not desired and to deliver operating steam to it when it is running as well as to shut it off when it is not. It is further desirable in such a controlling system to provide a means for idling the booster motor prior to entrainment and operation in order to warm it up sufficiently so that it will go to work promptly, as it is expressed, as well as to clear it of any condensation.

Furthermore, because of the importance 30 of reducing to a minimum the number of duties or operations which the engineer must perform in running a train, it is highly desirable and has been customary in the art to subordinate as much as possible the control 35 of the booster to the controlling devices of the main locomotive. To state it in other words, when the booster is once cut in, the control of its various functions is automatic and entirely subordinate or subservient to the 40 devices with which the engineer controls the main locomotive.

With the foregoing in mind the objects of my invention will be better understood which objects include the following:

45 The provision of a locomotive booster apparatus to which steam is supplied through a single conduit together with independent means for delivering first, idling steam to said conduit, second, entraining steam to said conduit, and third, operating steam to said conduit; the provision of separate valves for controlling each of said steam supplies together with independent motor means, preferably fluid actuated, for opening each of

said valves; the provision of means for subordinating the motor means for opening the valve which supplies the operating steam to the motor means for the valve which supplies the entraining steam; the provision of means for subordinating the motor for opening the valve which supplies the operating steam to the existence of steam pressure in the locomotive supply line which is the line conducting the steam from the locomotive throttle to the pistons—in other words final 55 operation of the booster motor is dependent upon operation of the locomotive although entrainment can be effected and maintained 60 regardless of whether or not the locomotive throttle be opened or closed; the provision of 65 a pilot device for the motor which opens the idling valve and of a separate pilot device for the motor which opens the entraining valve both of which pilot valves are subject 70 to the control of some moving part in the 75 devices used for adjusting the locomotive cut-off; the provision of a latch for initiating the operations of the booster which is adapted to actuate both of said pilot valves, the idling pilot valve being actuated during 80 the initial operation of said latch and the entraining pilot valve being actuated during the remainder or completion of the stroke 85 of said latch; the provision of means whereby the idling pilot valve will maintain the 90 booster latch in its entraining position after the entraining position has been once attained; and the provision of means whereby the latch will open the idling pilot valve in any position of the moving part of the cut-off mechanism with which it is associated but will actuate the entraining pilot valve only 95 in positions of long cut-off.

The foregoing objects together with any others which are incident to my invention or which may appear hereinafter, I obtain by means of an apparatus which is illustrated in preferred arrangement in the accompanying drawings, wherein:

Figure 1 is a diagram illustrating the 100 functional relationship existing between the various parts of my improved apparatus with most of them in section to illustrate their construction and the manner in which they operate; and

Figures 2, 3, and 4 are respectively side, 105 end and plan views of the latch and pilot valve arrangements associated with a power

reverse gear for adjusting the locomotive cut-off.

Referring to the drawings and particularly to Fig. 1 it will be seen that the booster 5 is arranged to drive the axle 1 thru the medium of the driving pinion 2, the idler gear 3 and the gear 4 fixed to the axle 1. The idler gear 3 is mounted upon the rocker 5 pivoted at 6 so that it can be thrown into mesh with the gear 4 and the booster thereby entrained, the gear 3 being at all times in mesh with the driving pinion 2.

The driving pinion 2 is mounted upon the booster crank shaft 6^a which is rotated by 15 the pistons (not shown), of the booster engine.

The rocker 5 is moved and entrainment accomplished by means of the piston 7, connecting rod 8, bell crank member 9 and link 10. When pressure is applied to the face of the piston 7 it moves to the right carrying with it the rod 8, forcing the bell crank member 9 to the right on the pivot 11 and causing the link 10 to move the rocker 5 so as to enable gear 3 to mesh with gear 4. Connection between link 10 and rocker 5 is made thru the medium of the pin 12 on the rocker and a slotted opening 13 in the link. The slot is so arranged with respect to the other parts that during the initial movement of the piston the gear may be completely entrained or meshed. Subsequent movement of the piston 7 in the same direction will simply cause the slot 13 to ride over the pin 12 and have no effect upon the rocker 5. The manner and purpose of this arrangement will appear hereinafter.

The rod 8, of course, is pivoted to the piston 7 and to the bell crank member 9 (as shown) and the piston works against the pressure of two springs one within the other around the rod 8. The inner spring 14 is of lighter construction and is always under compression while the outer spring 15, which is of heavier construction, is designed to exert its pressure only during initial return movement of the piston 7. It operates between the upstanding rib 16 and a washer or collar 17 adapted to abut or come up against the stop 18. During initial movement of the piston 7 to the right, therefore, it first acts only against the spring 14 until the space 7^a between the end of the piston 7 and the washer 17 is traversed when said piston carries with it the washer 17 to compress the heavier spring 15 as well.

Pressure is admitted to the face of the piston 7 thru the pipe 19-19' which is the only pipe or conduit conducting steam to the booster motor. During normal operation of the locomotive or when the booster is not being used the piston 7 is in its left-hand position since the booster is not then entrained and in this position it blocks the flow of operating steam to the booster thru

the ports 20 which communicate with the passage 21 leading to the valve chest of the booster, not shown.

A by-pass 22 of comparatively small capacity is formed in the wall of the cylinder 23 in which the piston 7 reciprocates. It will therefore be seen that whenever there is steam pressure in 19 it can pass the piston 7 thru this by-pass 22.

If it is desired to idle the booster before putting it into operation steam is admitted to the pipe 19 from a source at 24 thru the pipe 25 controlled by the valve 26. In the pipe 25 is arranged a small choke 27 of a capacity less than the capacity of the by-pass 22 so that the pressure admitted thru the pipe 25 will at no time be able to accumulate behind the piston 7 and force it to entrain the booster as it is not intended to have the booster entrained in this manner.

The valve 26 is opened by a small fluid motor comprising the piston 28 mounted for reciprocation in the cylinder 29. The piston 28 works against the pressure of the spring 30 and by admitting air pressure from a source at 31 thru the pipe 32 and past the pilot valve 33 (to be described later) it is possible to move the piston downwardly in order to open the valve 26.

When it is desired to entrain the booster, steam from the same source 24 is admitted to the pipe 34 controlled by the valve 35. A somewhat larger choke passage 36 is placed in the pipe 34 having a capacity greater than the capacity of the by-pass 22. It will therefore be seen that pressure will build up back of the piston 7 and force the gear 3 toward its meshing position with the gear 4, the by-pass 22 serving to keep the pinion 2 and the gear 3 slowly rotating in order to avoid clashing to as great a degree as possible during such entrainment operation.

Initial movement of the piston 7 is opposed only by the weaker spring 14 and before the ports 20 are uncovered the heavier spring 15 comes into play, thereby stopping further movement of the piston for the time being since the steam supplied through the valve 35 is not sufficient to compress spring 15. However, the direction of rotation is such (see the arrows in Fig. 1) as to cause the driving pinion 2 to pull the idler gear 3 into complete mesh with the axle gear 4, thus moving the pin 12 to the right hand end of the slot 13. When actual operation of the booster takes place (as will appear hereinafter) the piston 7 is free to move forward to uncover ports 20 because the slot 13 permits the link 10 to move to the right with relation to the pin 12.

The motor device for opening the valve 35 is of practically the same type as the motor device for opening the valve 26. However when the piston 37 in this motor has reached

the bottom of its stroke and the valve 35 is fully opened said piston uncovers a port 38 which establishes communication between the pipe 39 and the pipe 40 thru the latter of which the air pressure for operating the motor is introduced. The pressure in the pipe 40 can come from the source 31 but it is subject to an independent pilot valve 34 preferably of a construction exactly like the valve 33. Each of these pilot valves involves a double-ended valve 41-42, the member 42 being held against its seat by the spring 43 at such times when the booster control is not in operation. By depressing the plunger 44 member 41 is seated and member 42 is unseated so that communication is established thru the two branches of the pipe at each side of the pilot valve. The member 41 simply controls the exhaust thru the port 45.

So far we have described the means for idling the booster and the means for entraining it but have not mentioned the arrangements for delivering operating steam to the booster so that it will become a driving factor.

The throttle 46 controls the flow of operating steam to the booster thru the pipe 19-19' and this throttle is opened by means of the fluid motor 47 having the piston 48 acting against the spring 49. The section of pipe to the left of the throttle is referred to by the reference character 19 and the section to the right of the throttle by 19'. When the piston is moved downwardly against the spring 49 by fluid pressure entering thru the pipe 50 the piston rod 51 operates upon the rocking member 52 to raise the rod 53 connected to the throttle 46 and thereby open the latter. The full operating pressure of steam is, of course, sufficient to overcome the heavier spring 15 and the piston 7 is at once moved to uncover the ports 20 and permit the booster to become a driving factor. A hand-operated shut-off valve 54 is placed in the section 19' which is only used in cases of emergency.

The flow of operating fluid to the throttle operating cylinder 47 is subject to the control of a pilot device 55 which prevents communication between the pipes 39 and 50 until such time as pressure of steam exists in the section 19'. In other words the valve 56 is kept seated by means of the spring 57 and the fluid pressure below it until such time as the piston device 58 is forced downwardly by pressure entering thru the passage 59, at which time the valve member 60 is seated and the valve member 56 is opened. the former simply controlling exhaust thru the port 61 and the latter, as stated, controlling communication between the pipes 39 and 50.

As indicated in the beginning of this specification the pipe 19' receives its steam supply from the steam supply line of the loco-

motive, that is, the line between the locomotive throttle and the cylinders of the locomotive. In other words there is no pressure of steam in the pipe 19' until after the locomotive throttle has been opened and the locomotive has begun to go to work. The booster throttle, therefore, is subordinated to the control of the main engine and cannot be opened in the absence of pressure in the steam supply line to the main cylinders. This in itself is a feature which I do not claim except in combination with my peculiar arrangement for idling and for entraining the booster motor.

As already familiar to those skilled in this art the booster is intended to drive the locomotive only at starting or during comparatively slow speeds after which it is to be disengaged or cut out. It is advisable, however, to arrange so that the booster can be kept in operation even after the locomotive has begun to use steam expansively. At the same time it is desirable to be able to idle the booster whenever desired no matter whether the locomotive be standing still or be running at a fair rate of speed. In other words the engineer when he sees that it will be necessary to use the booster must be able to warm it up for a certain length of time before he entrains it regardless of the locomotive operating conditions existing at the moment.

The booster latch 62, therefore, which controls the whole system so far described is arranged to swing upon the pivot 63 so that during its initial movement the extended bearing surface 64 will come into contact with the plunger 44 in the idling pilot valve 33 and cause the valve 41 to close and the valve 42 to open. Pressure will then be admitted from the source 31 to open the idling valve and the booster can be idled as long as desired.

By continuing the movement of the latch in the same direction it will be seen that it will finally raise the plunger 44 in the entraining pilot valve 34 by virtue of the engagement of the latter with the face 65. When this occurs, of course, pressure from the source 31 is admitted to the entraining motor and the valve 35 is opened so that steam can enter the conduit 19 and entrain the booster.

While the booster is in operation the plunger in the pilot valve 33 is designed to hold the latch 62 in the final or entraining position as shown in full lines in Fig. 3 but when in the idling position (dotted lines in Fig. 3) the weight of the latch is sufficient to cause it to drop down away from the plunger 44 in the pilot valve 33 just as soon as the engineer takes his hand away.

The booster latch 62 is shown as associated with the screw 66 of a particular type of power reverse gear known as the precision

gear but which is not illustrated in detail because it forms no part of the present invention. Suffice it to say that adjustment of the valve cut-off of the locomotive is made by revolving the wheel 67 and with it the screw 66 and as the screw turns the latch 62 rides backwardly and forwardly along the screw 66. The middle position 68 (see Fig. 4) is the neutral or mid-gear position of the locomotive and the position 69 marks the full forward position of the cut-off and the position 70 the full reverse position of the cut-off.

It will be apparent that with the booster latch 62 at any position between 68 and 69 it would be possible to cause idling of the booster motor by virtue of the fact that the surface 64 is long enough to engage the plunger 44 of the pilot valve 33 in any position which the latch may occupy between these two points. It will be equally apparent that the face 65 of the latch 62 will be able to depress the plunger 44 in the pilot valve 34, which is the entraining pilot valve, only during comparatively long cut-offs of the locomotive valve gear.

The summary of the operation is as follows: Suppose the engine to be running and the engineer sees that it will be necessary to use the booster. He moves the latch 62 just enough to engage the pilot valve 33. This, as described, will open the idling valve 26 and as long as he holds the latch 62 in this position the booster motor will slowly idle and thereby clear itself of any condensation which may have accumulated and warm it up so that when its driving power is desired it will go to work without delay. When the cut off has been adjusted to substantially the 69 position and the moment arrives that the booster should be cut in or entrained the engineer simply continues the movement of the latch 62 to the full line position in Figure 3 whereupon the entraining valve 35 will admit steam to move the piston 7 in the manner already described. As soon as this valve 35 is opened air pressure will reach the throttle operating cylinder 47 because pressure already happens to exist in the pipe 19'. The throttle 46 will then open and the booster will become a driving factor. On the contrary had the idling and entrainment of the booster taken place while the locomotive was standing still it would not become a driving factor until after the main locomotive throttle had been opened and pressure existed in the pipe 19'.

The piston 7 is arranged so that complete entrainment of the gear 3 with the gear 4 takes place as described prior to the time that it uncovers the port 20 and during this time it will be acting only against the lighter inner spring 14. But when the full operating pressure of steam is admitted to the conduit 19-19' the piston 7 will have to

operate against the combined pressure of both springs 14 and 15 and in this way unnecessary shocks will be avoided. During return movement of the piston both springs will be effective until the port 20 is closed after which the heaviest spring will cease to exert any pressure and disentrainment will not take place until all steam is shut off from the pipe 19.

I claim:

1. The combination of a steam locomotive, a normally disentrained steam operated booster therefor, a conduit for delivering steam to the booster, a motor means for entraining the booster adapted to receive steam through said conduit, a valve for admitting steam to said conduit from one source to actuate said motor means for entraining the booster, and a throttle valve for admitting steam to said conduit from a second source for operating the booster.

2. The combination of a steam locomotive, a normally disentrained steam operated booster therefor, a conduit for delivering steam to the booster, a motor means for entraining the booster adapted to receive steam through said conduit, a valve for admitting steam to said conduit to actuate said motor means for entraining the booster, a throttle valve for admitting steam to said conduit for operating the booster and means for admitting steam through said conduit to idle the booster.

3. The combination of a locomotive, a normally disentrained booster therefor, a conduit for delivering operating steam to the booster, a motor means for entraining the booster adapted to receive steam through said conduit, a valve for admitting steam to said conduit to entrain the booster, a motor means for opening said valve, a throttle for the operating steam conduit, and a motor means for automatically opening said throttle which operates after said valve opening motor means has functioned.

4. The combination of a steam locomotive, a normally disentrained steam operated booster therefor, a conduit for delivering steam to the booster motor, a piston for entraining the motor arranged in the path of the steam through said conduit, a by-pass around said piston, a port controlled by said piston, means for admitting steam to said conduit in quantities not exceeding the capacity of the by-pass whereby to idle the booster, a second means for admitting steam to said conduit in quantities exceeding the capacity of the by-pass and sufficient to move the piston to cause entrainment but not operation of the booster motor as well as to open said port, and a throttle valve for admitting steam to said conduit and through said port whereby to operate said booster motor.

5. The combination of a locomotive, a

normally disentrained booster therefor, a conduit for delivering steam to the booster, a throttle for said conduit, a motor means for entraining the booster adapted to receive steam through said conduit, a motor device for opening said throttle, means for admitting steam from an independent source to said conduit to actuate the entraining motor means, and means for actuating said throttle opening motor device subsequent to the admission of independent entraining steam.

6. The combination of a locomotive, a booster motor, steam actuated means for entraining the booster, a valve for controlling the supply of entraining steam, a conduit for supplying the booster with operating steam, a throttle in said conduit, a fluid motor for opening the entraining supply valve, a fluid motor for opening the throttle, a conduit for conducting the fluid from the motor for the entraining valve to the motor for the throttle only after the entraining valve has been opened, and a pilot device in said fluid conduit subject to steam pressure conditions in the steam supply conduit in advance of the throttle, said pilot device being arranged to prevent flow of fluid to the throttle opening motor in the absence of steam pressure in said conduit.

30 7. A controlling system for a normally disentrained and inoperative locomotive booster motor comprising in combination, a conduit through which steam is supplied to said booster to control its various functions, entraining means normally blocking the flow of steam through said conduit, a comparatively small capacity by-pass around said entraining means, means for delivering steam through said conduit and said by-pass 40 to idle the booster without causing entrainment, means for delivering steam to entrain the booster and open said conduit but without causing operation of the booster as a driving factor, and means for delivering steam through said conduit to operate the booster as a driving factor.

8. The combination of a locomotive with its steam supply line, a normally disentrained booster therefor, a steam supply conduit for delivering operating steam to the booster from said supply line, a motor means for entraining the booster adapted to receive steam through said conduit, a valve for admitting steam to said conduit to entrain the booster, a motor means for opening said valve, a throttle for the operating steam conduit, a motor means for automatically opening said throttle which operates after said valve opening motor means has functioned, and a pilot device for preventing operation of the throttle opening motor means in the absence of pressure in the locomotive supply line.

9. The combination of a locomotive with its steam supply line, a normally disen-

trained steam operated booster therefor, a conduit for delivering operating steam to the booster from said locomotive supply line, a throttle for controlling the supply of operating steam through said conduit, a motor means for entraining the booster adapted to receive steam through said conduit, and a valve for admitting steam from an independent source to said conduit to actuate the motor means for entraining the booster but without causing the booster to become effective as a driving factor.

10. The combination of a locomotive with its steam supply line, a normally disentrained steam operated booster therefor, a conduit for delivering operating steam to the booster from said locomotive supply line, a throttle for controlling the supply of operating steam through said conduit, a motor means for entraining the booster adapted to receive steam through said conduit, a valve for admitting steam from an independent source to said conduit to actuate the motor means for entraining the booster, and means for idling the booster.

11. The combination of a locomotive with its controlling devices, a normally disentrained booster, means for idling the booster, means for entraining it, a pilot valve for controlling the idling means, and a second pilot valve for controlling the entraining means, both of said pilot valves being subordinated to the controlling devices of the locomotive.

12. A locomotive booster apparatus comprising in combination with a moving part in the cut-off controlling devices for the locomotive, a normally disentrained and inoperative booster motor, a controlling system for the booster including a pilot valve for idling the booster, a pilot valve for entraining the booster, and a booster latch associated with said moving part and adapted, when actuated, to open the idling pilot valve in any position of the moving part but the entraining pilot valve only in positions of said moving part which give long cut-offs.

13. The combination of a locomotive, a normally disentrained booster motor therefor, steam actuated mechanism for entraining said motor, a valve for supplying the steam for entrainment, a second valve for supplying steam to idle the booster prior to entrainment, a pilot valve for controlling the action of the entraining valve, and a second pilot valve for controlling the action of the idling valve.

14. A controlling system for a normally disentrained and inoperative locomotive booster motor comprising in combination, means for causing idle operation of the booster, means for causing entrainment of the booster, and a latch member initially movable for part of its stroke to cause actu-

ation of the idling means and subsequently movable for the balance of its stroke to cause actuation of the entraining means.

15. A controlling system for a normally disentrained and inoperative locomotive booster motor comprising in combination, means for causing idle operation of the booster, means for causing entrainment of the booster, and a latch member initially 10 movable for part of its stroke to cause actu-

ation of the idling means and subsequently movable for the balance of its stroke to cause actuation of the entraining means, the latch, after completion of its stroke, being held in its entraining position by the means for 15 idling the booster.

In testimony whereof, I have hereunto signed my name.

GEORGE H. ZOUCK.
